UNITED STATES PATENT OFFICE.

ALBERT WILLIAM SCHMID, OF BASEL, SWITZERLAND.

TREATING TEXTILE MATERIALS WITH CIRCULATING LIQUOR.

Application filed April 7, 1925. Serial No. 21,426.

To all whom it may concern:

Be it known that I, ALBERT WILLIAM SCHMID, a citizen of the Swiss Republic, and resident of Basel, Switzerland, have invented new and useful Improvements in Treating Textile Materials with Circulating Liquor, of which the following is a full, clear, and exact specification.

It is known to treat textile goods in form of hanks by placing the hanks on a perforated movable or fixed pipe and to apply the treating fluid to the textile material through the perforated pipe by pressure, so that the liquor trickles along the material and completely permeates it.

The object of the present invention is to improve this arrangement, by spraying the hanks or web lengths over a greater length with the treating fluid. For this purpose, according to the invention, not a perforated pipe, but a hollow saddle of U-shaped cross section having its outer side perforated, is used, which exposes to the textile material a large supporting and spraying surface, which can be up to 70% or more of the total circumference of the hank or web length to be treated, so that the action of the circulating fluid reaching the textile material through the hollow saddle can be very rapid and intensive.

For practical reasons it is impossible simply to increase the diameter of the hitherto known pipe so that the supporting surface reaches 70% of the circumference of the hanks, since such an increase would entail an undue increase in the size and cost of the apparatus. The use of a hollow saddle is here proposed just to avoid these disadvantages, while achieving the advantage of quicker and more intensive permeation of the textile material.

The accompanying drawing shows diagrammatically in Figure 1 an arrangement of the apparatus, and in Figure 2 a cross section of the hollow saddle itself.

The textile material is laid for example in hank form or in piece form over a hollow saddle *a* of U-shaped cross section. The treating fluid is held in readiness in a container *b*. The fluid is driven through the hollow saddle *a* by a pump *c* and owing to the pressure of the pump permeates the textile material *d*. The material remains stationary during the whole treatment. It has a large surface resting on the saddle *a* and since this large supporting surface is perforated over its whole extent, is abundantly sprayed. Preferably care is taken to make the total section of the perforations in the saddle *a* approximately equal to the section of the feed pipe *f*.

Practical experience has shown that the treatment time is reduced nearly in proportion to the increase in the supporting surface, and, when the treating fluid is a dye bath, that the evenness of the dyeing is considerably increased by the more rapid and intensive permeation rendered possible by the larger supporting surface.

Obviously the hollow saddle could be closed across the bottom in cross section, in frame form. It could also be formed of two oval tubes or the like one within the other, the outer being perforated only over the supporting surface for the textile material.

What I claim is:

In an apparatus for treating textile materials in hank or piece form with a circulating fluid, the combination with a fluid circulating device of a stationary carrier for the material consisting of a hollow saddle of U-shaped cross section, perforations being provided in its outer surface, so as to present a large supporting and spraying surface to the material.

In witness whereof I have hereunto signed my name this 26th day of March, 1925.

ALBERT WILLIAM SCHMID.
